UNITED STATES PATENT OFFICE.

AUGUSTUS A. GREENE, OF PROVIDENCE, RHODE ISLAND.

BUCKLE.

1,265,324.

Specification of Letters Patent.

Patented May 7, 1918.

Application filed May 26, 1917. Serial No. 171,267.

To all whom it may concern:

Be it known that I, AUGUSTUS A. GREENE, a citizen of the United States, residing at Providence, in the county of Providence and 5 State of Rhode Island, have invented a new and useful Improvement in Buckles, of which the following is a specification.

This invention relates to certain new and useful improvements in a buckle and more 10 particularly to a buckle embodying a locket construction.

The primary object resides in an improved locket-buckle having a pocket for the reception of a photograph, or other 15 identification, and a hingedly mounted medallion closable over the pocket and retained in such position by a cover member.

The invention further resides in the features of construction and the arrangements 20 and combinations of parts hereinafter described and claimed, reference being had to the accompanying drawings wherein—

Figure 1 is a front elevation of the improved locket-buckle.

25 Fig. 2 is a longitudinal section on line 2—2 of Fig. 1, showing the cover and medallion members in dotted lines in their opened positions.

Fig. 3 is a front elevation of a slightly 30 modified form of the invention, and

Fig. 4 is a longitudinal section therethrough on line 4—4 of Fig. 3.

Referring more particularly to the drawing, the numeral 1 designates the front plate 35 of the body of the buckle and 2 the side flanges which have the inclined cam slots 3 to slidably receive the belt-clamping bar 4. A belt securing member 5 is also pivoted between the side flanges 2 to which the fixed 40 end of the belt, not shown, is secured.

In the front face of the body plate 1 is 45 depressed or formed a pocket 6 in which may be placed a photograph, or other identification 7, the same being retained beneath a transparent covering 8 by a frame 9. The pocket is sufficiently deep so that when the photograph, the transparent covering and retaining frame are properly positioned 50 therein a shallow recess will be left within the pocket for the reception of the medallion or emblem carrying member 10. A closure or cover 11 is hinged to the body plate to one side of the pocket, as at 12, to flatly engage the outer or front face of said plate 55 and completely inclose the medallion and cover the pocket. A catch 13 is carried by

the cover 11 for engaging in a keeper notch 14 to thereby hold the cover operative. The cover is formed with a recess 15 to receive the medallion leaf, and said cover and body 60 plate are both formed with opposing grooves in which seats the connecting web or wing 16 which connects the medallion to its hinge knuckle 17, said knuckle being mounted on the hinge pin that connects the cover to the 65 body plate. The cover is preferably finished with a beveled border and has a knob or lift 18 extending from its free edge to facilitate opening of the locket.

The central hinged medallion may bear 70 configurations of any desired character, as of a religious or fraternal nature, the same being suitably impressed thereon. The pocket setting into the body plate is closed by the hinged medallion and the latter is 75 held within said pocket by the hinged cover.

In the modification, the locket pocket extends practically the entire area of the front plate and the cover 20 is hinged at one side and constitutes the front of the buckle. In 80 this construction, the design of the pocket is rectangular, the medallion member conforming thereto and the recess in the cover being correspondingly contoured receives the medallion.

In either form, the buckle still retains its 85 simple outline with practically no projections, and the locket is embodied within the outline of the buckle in a novel and practical manner.

Having thus described my invention, what 90 I claim as new and desire to secure by Letters Patent is—

1. A member having a pocket set in its front face and adapted to receive a photograph, a retaining frame in the pocket, a cover for the pocket hinged at one side thereof and formed with a recess registering with the pocket, said front face and cover having opposing grooves leading from their respective depressions to the hinge mounting of the cover and an emblem-carrying leaf fitting the pocket and registering cover recess and provided with a radial wing lying in the opposing grooves and formed with 100 a hinge knuckle for pivotally mounting the leaf to the cover mounting.

2. A member having a pocket set in its front face and adapted to receive a photograph, a retaining frame in the pocket, a 110 cover for the pocket hinged at one side thereof, and formed with a recess register-

ing with the pocket, said front face and cover having opposing grooves leading from their respective depressions to the hinge mounting of the cover, and an emblem-carrying leaf fitting the pocket and registering cover recess and formed with a hinge knuckle seating in the grooves and pivotally connected to the cover mounting.

3. A locket comprising a buckle body having a pocket formed in its front for receiving a photograph, a cover hinged to the buckle front on one side of the pocket and

having catch means for engaging on the opposite side of the pocket, and a medallion hinged in common with the cover and foldable over the buckle pocket. 15

In testimony whereof I have signed my name to this specification in the presence of two subscribing witnesses.

AUGUSTUS A. GREENE.

Witnesses:
